GEORGE JOHN KLOEPFER AND CARL F. KLOEPFER, OF SPRINGFIELD, OHIO.

SIGNALIZING DEVICE.

1,215,169.

Specification of Letters Patent. Patented Feb. 6, 1917.

Application filed July 30, 1916. Serial No. 111,052.

To all whom it may concern:

Be it known that we, GEORGE J. KLOEPFER and CARL F. KLOEPFER, citizens of the United States, and residents of Springfield, in the county of Clark and State of Ohio, have invented a certain new and useful Improvement in Signaling Devices, of which the following is a specification.

Our invention is an improvement in signaling devices, for use with motor vehicles, wherein a tubular casing is provided adapted to be arranged transversely of the wind shield and the supporting brackets thereof, having at each end a casing, and a signal in connection with each casing, mounted to swing into horizontal and vertical positions, and wherein an operating mechanism for the signal is mounted in the casing and in the tube, and wherein means is provided in connection with the operating mechanism for locking the signal in either position, and wherein a mirror is mounted on the rear face of each casing.

In the drawings:

Figure 1 is a perspective view of the improved device from the rear;

Fig. 2 is a partial rear elevation of one end of the device;

Fig. 3 is an enlarged perspective view of one end of the device with the signal in inoperative position and with the mirror removed; and

Fig. 4 is a section on the line 4-4 of Fig. 2.

The present embodiment of the invention is shown in connection with the supporting brackets 1 of a wind shield 2, and a signal device consisting of a plurality of substantially cylindrical casings 2 which are arranged at the ends of the wind shield, one casing being connected with each supporting bracket 1. Each of the casings has extensions or lugs 3 provided with openings for receiving bolts or screws to permit them to be secured to the supporting brackets, and the rear of each casing is adapted to be closed by the mirror 4, of circular or disk-like form, each mirror being held in place on the casing by means of a circular frame 5 or ring 5 which is secured to each casing by means of screws or the like.

The casings are connected by the tubular member 6 which is provided at each end with a marginal flange 7 abutting past the adjacent casing and secured thereto by rivets or the like, and each casing has a slot

or opening 8 at the axis of the tube and permitting communication between the bore of the tube and the interior of the casing.

A signal in the form of a tubular arm 9 is provided in connection with each casing, each arm being pivoted eccentrically of the casing, as indicated at 10 and each casing has an opening through which the arm extends, of a length to permit the arm to swing through an arc of ninety degrees, from a vertical position to an outwardly extending horizontal position.

A gear segment 11 is secured to the inner end of each tubular arm 9, and each segment is designed to mesh with the teeth of a rack bar 12 mounted to slide through the slot or opening 8, and the rack bar is guided and held in engaging position with the teeth of the segment, by means of a guide member 13 secured to the front wall of the casing above the rack bar. Each rack bar extends into the tubular member 6 and each rack bar is provided with a grip or handle 14 which extends through a longitudinally extending slot or passage 15 in the tubular member. Each of the grips or handles 14 is pivoted between bearing lugs on the rack bar in such manner that the grip or handle may be swung upwardly or downwardly, and at each end of the passage 15 peripherally extending extensions 16 are provided, forming locking slots or passages for engagement by the handles to lock the rack bar from movement. When either rack bar is moved into position of Fig. 3, the handle 14 is released and will fall into the position shown; that is, into the adjacent extension, thus locking the signal in inoperative position. When it is desired to swing the signal into horizontal or operative position, the handle is swung up until it registers with the passage 15 and the rack bar is moved inwardly. This swings the signal into horizontal position, and when the handle is released, it will fall into locked position.

An indicator 17 is secured to the outer end of each tubular arm 9, each indicator in the present instance being approximately diamond-shaped. An electric light 18 is arranged on each indicator at the outer end of the tubular arm. These lights are incandescent bulbs and they are connected with the contact member 19 at the peripheral surface of the casing 2 and insulated from the tube 6, by means of a conductor wire 20.

An electric circuit indicated at 21 has its

5 terminals in contact members 22 and 22^a which are so arranged that when the arm 9 is swung into horizontal position, the contact member 19 will engage the member 22, while the metallic tube 9 in which the bulb 18 screws will contact with the contact member 22^a and will interpose the bulb 18 in the circuit, which may be supplied with current through any suitable means, as for instance 10 a battery or the like.

15 In operation, the signals 9, 17, and 18 normally occupy the position shown at the right of Fig. 1. When the driver intends to turn to the left, for instance, he will grasp the handle 14 of that signal at the left, and will swing the said handle upwardly, and move the same inwardly to the inner end of the slot or passage. This movement will 20 swing the signal into the position shown at the left of Fig. 1, and the mere act of releasing the handle will lock the signal in operative position. The mirror on that side will give the driver a clear view of what is behind him, without the necessity of turning his head. When the turn has been made, the 25 movement of the handle 14 is reversed, and the act of releasing the handle locks the parts in inoperative position. When the driver intends to turn to the right, he will 30 turn the signal at the right.

The improved signaling device is simple and inexpensive, and the movement of the

signal into either position requires but a very short space of time. It will be understood that a cut-out switch will be imposed 35 in the circuit 21 to permit the bulb to be cut out of the circuit during daylight hours.

We claim:—

A signaling device, comprising a substantially cylindrical casing, a tubular member connected with the casing, a signaling arm pivoted in the casing, said casing having an opening for permitting the arm to swing into vertical or horizontal position, a gear segment at the inner end of the arm, a rack 45 bar mounted in the tubular member and engaging the teeth of the segment, a guide above the rack bar for holding the same in engagement with the teeth of the segment, a handle hinged to the inner end of the rack bar and mounted to swing upwardly and downwardly, the tubular member having a longitudinal slot for permitting the passage of the handle and having an extension at each end thereof for engagement by the handle when the same is released to lock the signal in operative and inoperative position, electric lighting apparatus mounted on the signal arm, and means controlled by the swinging of the arm into operative and inoperative position for controlling said light.

GEORGE JOHN KLOEPFER.
CARL F. KLOEPFER.
